UNITED STATES PATENT OFFICE.

ALBERT T. GAY, OF AUBURN, MAINE.

NUMBER BOARD.

1,414,271.

Specification of Letters Patent. Patented Apr. 25, 1922.

Application filed January 3, 1920. Serial No. 349,218.

To all whom it may concern;

Be it known that ALBERT T. GAY, a citizen of the United States of America, residing at Auburn, in the county of Androscoggin and State of Maine, has invented new and useful Improvements in Number Boards, of which the following is a specification.

The object of the invention is to provide a number board or designating apparatus for use in factories or in connection with cab stands and any other concerns requiring in the systematic transaction of business the indication of the proper order or succession in which the men or vehicles shall take up 15 certain duties or respond to calls as for example in the case of bell-boys and messenger boys in hotels and telegraph offices wherein after a member of the force has performed a certain duty or carried a message he takes 20 his place at the bottom of the list and does not again receive a commission until those who precede him in the order of succession have received calls or obtained commissions, and to this end the invention consists in a 25 construction and combination of parts of which a preferred embodiment is shown in the drawing, wherein:

Figure 1 is a front view of the device.

Figure 2 is a vertical sectional view of the 30 same.

Figure 3 is a transverse section on the plane indicated by the line 3—3 of Figure 1.

Figure 4 is a similar section on the plane indicated by the line 4—4 of Figure 1.

35 In the illustrated embodiment of the device which is especially adapted for use in factories and offices the preferably upright board or casing 10 is supported by a hollow base 11 in which is arranged a drawer or 40 other suitable receptacle 12, said casing having a guide or runway 13 open at its upper end to form an inlet as indicated at 14 and communicating at its lower end by a suitable outlet 15 with the drawer or receptacle 12.

45 This guide or runway is adapted to receive cards blocks or other numbered or distinguishably designated objects 16 which may be introduced at the inlet end of the guide or runway and are designed to drop by 50 gravity to a position of rest with the lowermost object in contact with a seat 17 which is formed by an offset between the body portion of the guide or runway and the outlet 15. The members or other designating characters on these objects are displayed through

an inspection slot 18 in the front of the casing and retaining means such as spring dogs 19 are arranged near the upper end of the guide to permit of the introduction of the objects while preventing withdrawal upwardly through said upper end to guard against the possibility of the cards, blocks or other objects being changed in the order of their appearance in the guide. Similarly in the lower or outlet end of the guide or 60 runway a retaining dog 20 is employed to prevent a card or block from being introduced into the guide or runway from below and thus changing the order or disturbing the succession designated by the objects. 70

The designation of the card or block at the bottom of the body portion of the guide or runway is supposed to indicate the person or vehicle which is next in the order of sequence to receive a commission or perform 75 a duty or respond to a call, and in the construction as illustrated the designation of such person or vehicle is Number 2, with the arrangement of cards shown indicating that those numbered 4 and 10 are successively to follow the displacement of the block 2 when the person or vehicle represented by said block has received a commission or call. The block numbered 5 as shown in the drawing Figure 1 is supposed 80 to represent the person or vehicle who has last received a commission and when the call for such person or vehicle comes the lowermost card or block is supposed to be moved 85 into discharging position or into alignment 90 with the outlet 15 and out of alignment with the main guide or runway by inserting the finger in a finger notch 21 which is provided at one side of the display slot 18 near its lower end. Similarly a finger notch 22 may 95 be provided at the upper end of the outlet branch of the chute to permit of pressing down upon the block designated 5 to cause it to pass the retaining element 20 and drop into the receptacle or drawer 12 from which 100 substantially it may be withdrawn, when the party or vehicle who has received a commission returns and is prepared to take his proper turn in the reception of a further commission. In this event obviously the 105 card or block thus withdrawn from the receptacle 12 should be replaced in the upper end of the chute to drop into position and thereby show the order in which he will follow his predecessors in that connection. 110

It is found in practice particularly in factories, that much confusion may be avoided in designating the men to successively perform duties where, for example, the even 5 distribution of the commission is necessary to avoid shirking on the one hand or a tendency to claim a commission out of order and to the disadvantage of another work- 10 man or employee on the other hand, to employ a definite mechanical means for indicating the proper sequence, and the device described, which can be constructed at a minimum cost and maintained at practically no expense, is especially adapted for this 15 purpose.

What is claimed is:

1. A number board having a vertical guide provided at its lower end with an offset outlet forming a seat and having in its 20 front wall a display slot, distinguishably designated objects for successive progressive movement through said guide, and means at the inlet and outlet ends of the guide for

preventing reverse or retrograde movement of said objects. 25

2. A number board having an upright casing provided with a guide having a front display slot, and a hollow base provided with a movable receptacle or drawer in communication with the lower end of said guide, 30 the guide being provided with a lower outlet end offset from the line of the body portion of the same to provide a seat, and the front wall of said guide being provided near the plane of said seat and in alignment with 35 said outlet with finger notches, distinguishably designated objects for progressive successive movement through said guide, and yielding dogs located near the upper inlet end of the guide and near the outlet end 40 thereof for preventing reverse or retrograde movement of objects therein.

In testimony whereof he affixes his signature.

ALBERT T. GAY.
